FRED S. OLIVER, OF SAN FRANCISCO, CALIFORNIA.

CARBURETER.

1,315,191.

Specification of Letters Patent. Patented Sept. 2, 1919.

Application filed March 20, 1917. Serial No. 155,991.

To all whom it may concern:

Be it known that I, FRED S. OLIVER, a citizen of the United States, residing at the city and county of San Francisco and State of California, have invented new and useful Improvements in Carbureters, of which the following is a specification.

This invention relates to carbureters of the type used for converting the ordinary 10 grades of gasolene into a combustible mixture suitable for cooking, heating, lighting and other purposes. The object is to simplify and improve the construction and operation of the carbureting apparatus.

One form which my invention may assume is exemplified in the following description and illustrated in the accompanying drawings, in which—

Figure 1 shows a vertical, central sectional view of a device embodying my invention;

Fig. 2 shows a detail sectional view of the vaporizer or auxiliary carbureter employed in one of the gasometers.

As shown herein, the device comprises a primary gasometer A and a secondary gasometer B, placed side by side, and each made up of a double walled lower stationary tank 12 and a double walled upper movable bell 30 section 13, the latter having its outer wall telescopically received in a water seal 14 between the double walls of the stationary tank and its inner wall spaced inwardly from the inner wall of the stationary tank 35 and carrying at its lower end a cloth or screen hood 15 secured to the bottom of the tank.

Centrally arranged within the gasometers A and B are cylinders 16 and 16' respectively, open at their upper ends, and having communications at their lower ends with valved pipes 17 and 17' running separately to supply tanks 18 and 18' respectively, preferably located underground. The tank 45 18' may be filled through a filling pipe 9 and thereafter tightly closed. A hollow piston 19, carried on the end of a hollow rod 20 secured to the bell, works in the cylinder. The piston has an upwardly opening check 50 valve in its bottom and the rod is provided with perforations whereby fuel drawn in to the cylinder on the upward stroke of the piston is permitted to pass outwardly through the upper end of the cylinder on 55 the return stroke of the piston.

Surrounding the upper end of the cylinder is a perforated dish 21 forming a sprinkler to receive the gas which is discharged from the cylinder. Beneath the dish 21 is a casing 22 surrounding the cylinder and spaced therefrom, with a packing 23 of loof or other suitable spongy material into which the fuel from the dish falls. The object is to saturate the packing with gasolene and then by passing air therethrough to 60 atomize the liquid.

The air supply for the carbureter is introduced through a pipe 24 at the inner end of which is an upwardly opening check valve 25. In the case of the first gasometer, a 70 vaporizer or auxiliary carbureter 26 is added to pick up the gasolene collected at the bottom of the main carbureter from the drippings of the packing 23. This vaporizer is best shown in Fig. 2 and comprises an air 75 inlet pipe 27 with a check valve 28 and a cup 29 encircling the cylinder 16 and arranged beneath a conical deflector 30, which latter directs the gasolene from the packing into the cup. This plate is frusto-conical 80 and is secured by its enlarged lower edge to the wall of the casing. The upper opened end of the partition surrounds the cylinder 16 and is spaced therefrom to form an annular passageway. The plate thus arranged 85 provides a V-shaped groove into which the surplus liquid fuel will fall and from which it may be drained by the tube 30' which communicates with the cup therebeneath. Within the cup is a series of vertically arranged 90 air nozzles 31 carried by a plate 32, this plate forming a false bottom for the cup, said nozzles having communication with a space below the false bottom. A series of curved nozzles 33 for the fuel are carried by 95 the plate with their lower ends spaced above the same and their upper ends passing into close proximity with the air nozzles, whereby the air in passing through the nozzles 31 under the suction created by the rising 100 of the bell draws the fuel up through the nozzles 33 and atomizes the same.

The gaseous mixture drawn through the packing 23 enters the bell of the gasometer and by the descent of the latter is forced 105 through the screen 15 into the space between the inner walls of the bell and tank. An outlet pipe 34 extends vertically along the inner wall of the tank to a point near the top thereof, and, in the case of the first gas- 110

ometer, the supply pipe 24 for the second gasometer is connected therewith, while in the case of the second gasometer, suitable connections 35 are provided to draw off the 5 contents, either for immediate consumption or to a storage tank.

The bottom of each tank will contain a small level of liquid fuel precipitated in the course of operation and into this the screen 10 15 will be dipped when the bell is in its lowermost position. The screen thus becomes saturated and as the vapor from the bell passes therethrough it will be enriched and a considerable portion of the precipitated fuel will thus be taken up. When the 15 20 level of the liquid in the bottom of the tank becomes too high, it is drawn off by an overflow pipe 36. This pipe in the case of the first tank A runs to a trap 38 where the liquid is collected to a predetermined level and allowed to flow into the supply tank 18 through a pipe 39. A valved discharge pipe 40 communicates with the bottom of the trap and is controlled by a gravity apparatus 41, which, when the liquid in the trap becomes too heavy for further use opens to allow the same to be drawn off. This gravity valve is shown and described in United States Letters Patent, No. 1,161,243, granted to me November 23rd, 1915, and need not be further described herein.

The overflow pipe of the second tank B has branches 42 and 43, one leading to the supply tank beneath the first gasometer and the other leading to the supply tank beneath the second gasometer. A valve 44 is placed in the connections to control the passage of fuel through these branches to retard the flow of liquid to the pipe 43 and cause it to overflow through the pipe 42. Thus the precipitated gasoline of the second gasometer will be returned to the supply tanks for further and later carburization, while the precipitation of the first gasometer will be returned for reuse in so far only as it remains sufficiently volatile for carburization and the residue which is free of all particles that could be atomized will be discharged into the drain pipe 40.

50 It is desirable, however, to limit the quantity of gasoline introduced into the second carburetor, and therefore I provide the cylinder 16 with a port near its middle portion with which communicates a tube 45 leading to the top of the cylinder. Thus when the piston reaches the port the suction is broken and the charge of gasoline drawn in thereby restricted.

It now remains to describe the automatic 60 operation of the bells whereby the gasoline is pumped in and carbureted and transferred from the first to the second gasometer. The bell of the first gasometer is connected by a rod 46 to a piston 47 working in a cylinder 48 which is fitted at its lower

end with a pipe 49. The pipe 49 has a supply main 50 communicating with it and also a discharge pipe 51. A two-way valve 52 arranged at the junction of these pipes alternately establishes communication between the pipe 49 and supply pipe and discharge conduit. The handle of the valve is connected to a lever 53 actuated by a cable 54, the latter running over sheaves 55 and connected to the piston 47. The bell of the second gasometer has connected to it a cable 56 running to a lever 57 which actuates a valve 58 located in the discharge pipe 51 behind the two-way valve 52. The connections between the cables 54 and 56 and their respective levers are such as to secure an actuation of the levers in both directions and at times when the bells are nearing the ends of their movements. This is accomplished by allowing the cables to pass through openings 59 in the levers and providing said cables with spaced blocks 60 and weights 61, to limit the relative movement between cables and levers.

The bells of the gasometers are both in their lowermost positions when starting, at which time the valves will be open to admit water to the lower portion of the cylinder 48. The piston is thus raised, lifting the bell of the first gasometer and the weight 61 on the end of the cable draws the latter down until the block thereon strikes the lever 53 and depresses the latter, thus causing the valve 52 to be turned to position where the supply is cut off and the discharge 100 opened. This permits the water to escape from the cylinder, and the piston is gradually lowered by the weight of the bell. The bell of the first gasometer is weighted to overbalance the second, and hence the pressure on the gas transferred from the first gasometer to the second will be sufficient to raise the bell of the second gasometer. The latter, when in raised position, will, through its connections, close the valve 58 against 110 the escape of water from the cylinder 48. Until the gas is drawn off from the second gasometer to permit the bell thereof to settle, the escape of water from the cylinder will be prevented. Upon a subsequent actuation of the first bell, it will remain in raised position unless the second bell has settled sufficiently to open the discharge valve 58.

The gasoline, which has trickled through the packing 23 of the first carburetor without becoming vaporized, will naturally be of a heavier grade and by introducing fresh air thereto through the auxiliary carburetor 26, in the manner shown, many of the heavier hydrocarbons will be atomized.

The water seal of the gasometers, in addition to preventing leakage of gas, will absorb heat from the surrounding atmosphere, and from repeated agitation due to the rising and falling of the bells will transmit

this heat to the inner walls of the tanks which tend to become quite cold due to evaporation of the gasoline.

Various changes in the construction and arrangement of the several parts herein shown and described may be employed without departing from the spirit of my invention as disclosed in the appended claims.

Having thus described my invention, what I claim and desire to secure by Letters Patent is:

1. A carbureter comprising a double walled tank, said walls forming between them a water seal, a bell on the tank having double walls, the outer one fitting into the water seal, a carbureter within the tank, means to supply fuel to the tank, means for raising the bell to draw air and fuel into the carbureter, a fabric hood sleeve encircling and secured to the lower end of the inner wall of the bell and a discharge pipe for the carbureted mixture located between the inner walls of the tank and bell whereby the carbureted mixture is passed through the fabric on its way to the discharge pipe, and said fabric, on the actuation of the bell, is caused to be dipped into fuel collected in the bottom of the tank from precipitation.

2. In a gasometer, a tank, a bell therein, a casing arranged centrally within the bell and having its upper end open, a cylinder open at its upper end and arranged within the casing, means to supply fuel to the cylinder, packing between the casing and cylinder, a piston having a rod secured to the bell and operating in the cylinder, and a fuel receiver secured to the upper end portion of the cylinder and overlying the open upper end of the casing, said fuel receiver having ports to allow the fuel entering same to seek the packing, and means to supply air to the casing below the packing.

3. In a gasometer, a tank, a bell therein, a casing arranged centrally within the bell and having its upper end open, a cylinder within the casing, means to supply fuel to the cylinder, a piston connected to the bell and operating in the cylinder, packing between the casing and cylinder, a conical deflector secured at its base to the casing below the packing to form an annular fuel passageway with the casing, a pipe communicating with

and depending from said passageway, and a cup having atomizing means arranged to receive the fuel from said pipe.

55

4. In a gasometer, a tank, means to supply fuel thereto, a bell therein, a casing in the tank, packing in the casing, means to deliver fuel to the upper end of the packing, means at the lower end of the packing to collect fuel seeping through the packing, and an atomizing device including a cup having a false bottom to receive the fuel from said collecting means and having air pipes extending through the false bottom, means to supply air beneath said false bottom, and a series of curved nozzles spaced at their lower ends above the false bottom and having their upper ends arranged adjacent the upper ends of the air pipes.

70

5. In a gasometer, a tank, a bell therein, a casing in the tank, a cylinder open at its ends within the casing, means to supply fuel to the cylinder, packing between the cylinder and casing, a piston in the cylinder connected to the bell, means to supply air to the lower end of the packing, a fuel receiver at the top of the cylinder to receive fuel delivered by the piston and formed to distribute same to the top of the packing, and a tube connected to the cylinder at an intermediate point along the cylinder length to break the piston suction so as to limit the quantity of fuel delivered by the piston to the receiver.

75

6. In a gasometer, a tank, a bell therein, a casing within the bell having its upper end open, a cylinder within the casing, means to supply fuel to the cylinder, a piston connected to the bell and operating in the cylinder, packing between the casing and cylinder, a deflector arranged in the casing below the packing and formed to receive fuel seeping through the packing, an atomizer arranged below the deflector and formed to receive fuel from the deflector, and separate means to supply air to the atomizer and to the casing below the packing.

85

In testimony whereof I have hereunto set my hand in the presence of two subscribing witnesses.
